UNITED STATES PATENT OFFICE

HARRY H. BARBER, OF AURORA, ILLINOIS, ASSIGNOR TO BARBER-GREENE COMPANY,
A CORPORATION OF ILLINOIS

LOADING MACHINE

Application filed May 10, 1930. Serial No. 451,226.

This invention relates to a loading machine of that type involving a boom having an endless bucket chain thereon with material feeding elements at the lower end of the boom for feeding material to the buckets. The invention concerns itself primarily with means for controlling the feeding elements and assuring that the same always occupy a vertical position irrespective of the movements of the boom.

The invention comprises the novel structure and combination of parts hereinafter described and more particularly pointed out and defined in the appended claims.

In the accompanying drawings, which illustrate a preferred form of this invention and in which similar reference numerals refer to similar features in the different views:

Figure 1 is a fragmentary side elevational view of a loading machine embodying this invention.

Figure 2 is a fragmentary top plan view of the feeding elements and adjacent parts with the boom removed.

Figure 3 is a part sectional, part plan view of a connecting bar for connecting the boom with the vehicle frame.

Figure 4 is a fragmentary plan view through another connecting rod for connecting the feeding elements with the vehicle frame.

The machine to which this invention is applied consists of a vehicle frame which is generally designated by the reference numeral 1 and is supported for traveling movement. This frame supports suitable tracks 2 for rollers 3 which are carried by the boom whereby a floating arrangement is secured between the boom and frame. The boom, which is generally designated by the reference numeral 4, sustains an endless bucket chain 5 which travels therearound, as is usual in the art. The material is adapted to be fed to the buckets by means of a pair of feeding discs 6 which have vertical shafts extending into gear casings 7. Each gear casing 7 has a stub shaft 8 (Figure 2) projecting therefrom, and sprocket gears 9 are carried by the ends of these shafts for operating the conveyor chain. It might be men-

tioned that the boom is pivoted upon these stub shafts 8.

The gear casing of each disc 6 is provided with a casting 10, as shown in Figure 2. These gear casings are also provided with castings 11 which are spaced from the casting 10. A rod 12 is supported by the castings 11 for a purpose that will presently appear. A pair of radius rods 13 are pivoted to the rods 12 at their forward ends. The rear ends of the radius rods 13 are pivoted to a shaft 14 which is secured to the vehicle frame. Above the shaft 14 there are a pair of angle clips 15 which are secured to the frame of the vehicle, as shown more clearly in Figure 2. A radius rod 16 is pivoted at its rear end upon each of the angle clips 15. The forward ends of the radius rods 16 are provided with adjustable or extensible hooks 17 which are adapted to hook over suitable pins 18 secured upon the casting 10. The rods 16 are parallel with the radius rods 13 whereby a parallel motion is obtained and, as these rods are pivoted to the feeding elements for the conveyor, it is obvious that, as the boom is raised and lowered, the feeding elements are constrained to travel in a true vertical direction, with the result that, whenever the boom is lowered, the axis of the feeding discs will be vertically positioned. It will be noted that the conveyor boom is mounted to roll upon the bearings 2 and will roll upon these bearings during the raising or lowering movements thereof. However, none of these motions will cause any tilting movement of the feeding elements on account of the parallel motion rods or links that connect the feeding elements with the vehicle frame.

When it is desired to elevate the boom to horizontal position, the rods 13 and 16 can readily be released at their forward ends. The boom, however, is adapted to be elevated a predetermined extent without releasing the rods 13 and 16, as is shown in dotted lines in Figure 1, and, in such dotted line position, the machine may readily be moved about in a yard or the like.

I am aware that many changes may be made and numerous details of construction may be varied through a wide range without

departing from the principles of this invention, and I, therefore, do not purpose limiting the patent granted hereon otherwise than necessitated by the prior art.

5 I claim as my invention:

1. In a loading machine comprising a frame, a boom supported upon said frame, horizontal feeding disks having vertical axis attached to said boom, vertically spaced bearings associated with each feeding disk and parallel arms pivoted to said frame and to said bearings, said arms being releasable whereby said boom may be elevated to horizontal position.

10 2. In a loading machine comprising a frame, a boom floatingly mounted upon said frame, horizontal feeding members having vertical axis pivotally mounted upon the lower end of said boom, and a pair of parallel bars pivotally connected to said frame and to each feeding element for maintaining the axis of said feeding elements in vertical position during the raising and lowering of the boom.

15 3. In a loading machine including a frame, a boom floatingly mounted upon said frame, feeding elements pivotally mounted upon said boom and a pair of parallel bars pivoted to said frame and pivotally connected to each feeding element for maintaining said feeding elements in a predetermined position during all movements of the boom.

20 4. In a loading machine comprising a frame, a boom mounted thereon for tilting and shifting movements, a bucket conveyor carried by said boom, feeding elements having vertical axis pivotally connected to said boom for supplying material to said bucket conveyor, and a pair of parallel links pivoted to the frame and pivotally connected to each feeding element for maintaining said elements in a predetermined position during movements of the boom.

25 45 In testimony whereof I have hereunto subscribed my name at Aurora, Kane County, Illinois.

HARRY H. BARBER.
